No. 613,726.

Patented Nov. 8, 1898.

B. J. SHAFFER.

TONGUE SUPPORT FOR HARVESTERS.

(Application filed Dec. 31, 1897.)

(No Model.)

Inventor

Benjamin J. Shaffer.

By his Attorneys,

C. A. Snow & Co.

UNITED STATES PATENT OFFICE.

BENJAMIN J. SHAFFER, OF SINGER'S GLEN, VIRGINIA.

TONGUE-SUPPORT FOR HARVESTERS.

SPECIFICATION forming part of Letters Patent No. 613,726, dated November 8, 1898.

Application filed December 31, 1897. Serial No. 664,926. (No model.)

To all whom it may concern:

Be it known that I, BENJAMIN J. SHAFFER, a citizen of the United States, residing at Singer's Glen, in the county of Rockingham and 5 State of Virginia, have invented a new and useful Tongue-Support for Harvesters, of which the following is a specification.

My invention relates to a tongue-support for harvesting-machines, and has for its object 10 to provide a simple, compact, and efficient construction and arrangement of parts adapted for yieldingly attaching a rolling support or colter-wheel to the tongue of a harvesting or equivalent machine.

15 Further objects and advantages of this invention will appear in the following description, and the novel features thereof will be particularly pointed out in the appended claims.

20 In the drawings, Figure 1 is a side view of a tongue-support embodying my invention applied in the operative position to a tongue. Fig. 2 is a detail view in perspective of the lower spring-clamps and contiguous parts.

25 Fig. 3 is a vertical sectional view of the same. Fig. 4 is a detail transverse section of one of the spring-arm seats. Fig. 5 is a detail view of a portion of the journal and the interlocking washer detached.

30 Similar numerals of reference indicate corresponding parts in all the figures of the drawings.

1 designates a spring-arm having horizontally-disposed upper and lower extremities 35 and an inclined body portion, said terminal portions being removably fitted in clamps 2 and 3, of which the former is constructed for attachment to the under side of a machine-tongue 4, while the latter carries a rolling

40 support or wheel 5. Each clamp consists of a base-plate 6, channelled longitudinally at one side to form an arm-seat 7, said arm-seat being provided at an intermediate point with a perpendicularly-disposed stud 8 for engagement with an opening 9 in the arm 1 when the latter is seated in the clamp. Furthermore, each clamp is provided with terminal 45 transversely opposite perforated ears 10, and the seat in the plate is spanned to hold the 50 arm therein by clamp-bars 11, held in place by bolts 12, which engage registering openings in said clamp-bars and the ears of the clamp-

plate. The seat in the plate is preferably of less depth than the thickness of the spring-arm, while the stud which projects from the 55 plate is approximately of a length equal with the thickness of the arm, and the clamp-bars are recessed at their inner sides to fit the exposed surface of the arm. The plate of the lower clamp is provided with a depending 60 journal 13, mounted in a vertical bearing 14, provided with arms 15, between which said rolling support 5 is arranged, a scraper 16 projecting rearwardly from one of said arms and having a transverse portion positioned near 65 the tread of the wheel to prevent accumulation of soil thereon. Said journal is reduced near its lower end to form a shoulder 17, against which bears a washer 18, provided with notches to engage studs 19 on the shoulder, and bearing against the washer and 70 threaded upon the lower reduced extremity of the journal is a nut 20.

From the above description it will be seen that the upper clamp is constructed to allow 75 the displacement of the upper end of the spring-arm by the removal of the clamp-bars which span the seat in the clamp-plate, and in practice I preferably secure said clamp-bars in place by the same bolts. Furthermore, it will be seen from the foregoing 80 description that the lower end of the spring-arm is removably seated and secured in the clamp-plate which carries the rolling support and that the frame in which said rolling support is mounted is swiveled upon the lower 85 clamp-plate to allow it to follow the direction of movement of the tongue.

The construction as described is simple and provides for attachment to the tongue of 90 a vehicle of any desired construction without special preparation of the vehicle-tongue.

Various changes in the form, proportion, and the minor details of construction may be resorted to without departing from the spirit 95 or sacrificing any of the advantages of this invention.

Having described my invention, what I claim is—

1. A tongue-support for vehicles, having a 100 spring-arm provided at one end with a rolling support, and a clamp for attachment to a tongue and having a clamp-plate provided with a longitudinal seat for the reception of

the contiguous end of the arm, and of a depth less than the thickness of the same, a stud projecting perpendicularly from the seat and engaging an opening in the arm, clamp-bars 5 transversely spanning the clamp-plate in contact with the exposed surface of the arm, and means for securing said bars in operative contact with the arm, substantially as specified.

2. A tongue-support for vehicles, having a 10 spring-arm and means for attaching one end thereof to a tongue, a clamp having a plate provided in its upper surface with a seat to receive the lower end of the arm, a stud projecting perpendicularly from said seat at an

intermediate point, clamp-bars transversely 15 spanning the clamp-plate in contact with the exposed surface of the spring-arm and bolted to the plate, a journal depending from the clamp-plate, and a wheel-frame having a hub removably mounted upon said journal, substantially as specified.

In testimony that I claim the foregoing as my own I have hereto affixed my signature in the presence of two witnesses.

BENJAMIN J. SHAFFER.

Witnesses:
